(57) **CLAIM**

The ornamental design for an osteotome blade, as shown and described.

DESCRIPTION

FIG. 1 is a perspective view of an osteotome blade in accordance with a first embodiment of the new design; FIG. 2 is a front view of the osteotome blade of FIG. 1; FIG. 3 is a rear view of the osteotome blade of FIG. 1; FIG. 4 is a left side view of the osteotome blade of FIG. 1; FIG. 5 is a right side view of the osteotome blade of FIG. 1; FIG. 6 is a top plan view of the osteotome blade of FIG. 1; FIG. 7 is a bottom plan view of the osteotome blade of FIG. 1;

FIG. 8 is a perspective view of an osteotome blade in accordance with a second embodiment of the new design; FIG. 9 is front view of the osteotome blade of FIG. 8; FIG. 10 is a rear view of the osteotome blade of FIG. 8; FIG. 11 is a left side view of the osteotome blade of FIG. 8; FIG. 12 is a right side view of the osteotome blade of FIG. 8;

FIG. 13 is a top plan view of the osteotome blade of FIG. 8; and,

FIG. 14 is a bottom plan view of the osteotome blade of FIG. 8.

The broken lines, and unshaded surfaces bound by broken lines, illustrate portions of the osteotome blade which form no part of the claimed design.

1 Claim, 14 Drawing Sheets
